FOLDING TABLE

Filed Nov. 13, 1929

Inventor
Jacques Jean LAFFILLÉE
By Addison A. Armstrong
His Attorney

UNITED STATES PATENT OFFICE

JACQUES JEAN LAFFILLÉE, OF PARIS, FRANCE

FOLDING TABLE

Application filed November 13, 1929, Serial No. 406,939, and in France November 27, 1928.

My invention relates to a folding table which is particularly adapted to be carried with the spare wheel of an automobile with a view to not encumbering the vehicle when such table is folded and not in use.

The principal features of my table reside in the fact that it is composed of an upper plate having a flange forming a recess into which are adapted to be folded the legs of the table in a way which will be hereinafter more particularly pointed out.

According to my invention when the table is folded it is adapted to be carried with the spare wheel of a motor vehicle by applying the same against such wheel in a way that it is easily removed for use.

The attaching of the table to the spare wheel can take place in a number of ways but I prefer to utilize bolts of sufficient length to traverse the plate of the table through holes provided thereon.

It is to be remarked that the table thus affixed to the spare wheel constitutes a protecting plate which may be suitably decorated if desired.

My invention will be more readily understood by those skilled in the art to which it relates in the following description when taken in connection with the accompanying drawing forming part of this specification and in which—

Fig. 1 is a perspective view of my improved table in unfolded position ready for use:

Fig. 2 is a similar view thereof but folded and in position with the spare wheel of a motor vehicle;

Fig. 3 is a view looking from beneath;

Fig. 4 is a view partly in section illustrating a number of phases of the unfolding operation; and

Fig. 5 is a view with parts in section of the table in position with the spare wheel of a motor vehicle.

Referring to the drawing more in detail, the table top comprises a disk 1 having a down turned flange 2. The legs 3 constituted of channel bars are pivoted at 4 beneath the top. A third leg 5 is rigid with a cross piece 6 also of channel bars has its two extremities

bent over (Fig. 1). These two extremities are traversed by a shaft 8 lodged in the cross piece 6 and secured at its two extremities to the two legs 3 which it traverses.

In the channel bars constituting the legs 3 are lodged, during folding of the table, two extensions 9 of said legs pivoted on the shaft 8. An extension 10 of the leg 5 is similarly lodged, during folding, in the channel bar constituting the leg 5 and articulated on the shaft 8. In the position of folding (Fig. 3) the opening of the channel bars of the two legs 3 are faced in opposite directions, with respect to the leg 5. Suitable cross pieces are adapted to assemble the legs 3 and the leg 5 such as the braces 11 for example (Fig. 3). In folding position, the leg 5 comes to lodge itself in a notch 12 of a wooden bracket 13 rigid with the disk or top 1 (Figs. 3 and 4). Movable pin 14 maintains the pins in this position.

For unfolding the table, the pin 14 is withdrawn and the legs 3 are raised by swinging on their pivots 4 and in the direction of the arrows (Fig. 4) whereas by rotation of leg 5 about its shaft through more than half a turn in the direction of arrow F' said leg is brought into the position indicated by dot and dash lines (Fig. 4), the extremity 5' of said leg wedging in the notch 15 of a fixed stop 16 beneath the top 1. To complete the unfolding, it suffices then to fold back, according to the direction of the arrows F'' and F''' (Fig. 4) and under a half turn, the three extensions 9 and 10, give the three legs their proper length (Fig. 1). These extensions bear against the extremities of the three feet, of which the channels open in the direction of the ground, and thus assure proper setting of the table.

The folded table (Fig. 3) is applied by its flange 2 against the pneumatic tire α of the spare wheel, in such wise that the wall of this tire comes to press the folded edge of the table; the latter thus immobilized can not give way to any disagreeable noise. The disk 1 is fixed in this position due to two bolts 17 traversing the wheel carrier γ , the cheek ε of the wheel, against which bears the wooden bracket 13 of the top and through

holes 18. An ornament 19 can be secured at the same time by bolts as shown at 19 if desired.

While I have described what I deem to be the preferred form of my invention I do not wish to be limited thereto as there might be many changes made in the form of construction and arrangement of parts without departing from the spirit of my invention as comprehended within the scope of the appended claims.

Having described my invention what I claim as new and desire to secure by Letters Patent is:

- 15 1. A portable table of the type described, comprising a cup-shaped table top, a pair of legs pivoted to said table top and adapted to be folded therein, a third leg opposite said first two legs pivoted to said table top 20 and adapted to be folded therein, a cross piece rigidly secured at the middle to said third leg and means for releasably securing said cross piece to said first two mentioned legs.
- 25 2. A portable table of the type described, comprising a cup-shaped table top, a pair of channel shaped legs pivoted to said table top, a third channel shaped leg, a cross piece rigidly secured to the middle on said third 30 leg, means for securing said cross piece removably to said first two legs and means for receiving said third leg carried by said top when said third leg is moved to folded position.
- 35 3. A portable table of the type described, comprising a cup-shaped table top, a pair of channel shaped legs pivoted to said table top, a third channel shaped leg, a cross piece rigidly secured to the middle on said third 40 leg, a shaft carried by each extremity of said cross piece adapted to traverse said first mentioned legs and means for removably securing said shafts to said first mentioned legs.
- 45 4. A portable table of the type described, comprising a cup-shaped table top, a pair of channel shaped legs pivoted to said table top, a third channel shaped leg, a cross piece rigidly secured at its mid point to said third leg, a bolt carried by each extremity of said 50 cross piece adapted to traverse said first mentioned legs, bolts for securing said cross piece to said first mentioned legs, an extension in each of said first mentioned legs adapted to be traversed by said bolts, and an extension in said third leg abutting against said cross piece.
- 55 5. A portable table of the type described, comprising a cup-shaped table top, a pair of legs pivoted to said table top and adapted to be folded therein, a third leg, a cross piece rigidly secured at its mid-point to said third leg, means for removably securing the extremities of said cross piece to said first mentioned legs and means for securing said table

top to the wheel carrier of a motor vehicle when said legs are in folded position.

6. A portable table of the type described, comprising a cup-shaped table top, a pair of legs pivoted to said table top and adapted to be folded therein, a third leg, a cross piece rigidly secured at its mid-point to said third leg, means for removably securing the extremities of said cross piece to said first mentioned legs, and a plurality of holes formed in said table top for receiving the securing bolts of the spare wheel of a motor vehicle.

In testimony whereof I hereunto affix my signature.

JACQUES JEAN LAFFILLÉE.
